United States Patent

Des. 237,370
Patented Oct. 28, 1975

237,370

FIRE ENGINE CAB BODY

Don L. Johnson, San Jose, Calif., assignor to
FMC Corporation, San Jose, Calif.

Filed Nov. 5, 1973, Ser. No. 412,923

Term of patent 14 years

Int. Cl. D12—13

U.S. Cl. D12—13

FIG. 1

FIG. 2

FIG-3

FIG. 4

FIG. 1 is a side elevational view of a fire engine cab body showing my new design;

FIG. 2 is a left front perspective view thereof;

FIG. 3 is a right front perspective view thereof; and

FIG. 4 is a left rear perspective view thereof.

The broken lines in the drawing are for illustrative purposes only.

I claim:

The ornamental design for a fire engine cab body, as shown and described.
